UNITED STATES PATENT OFFICE.

EVA MAY BROWN, OF GARDINER, MAINE.

DESIGN FOR A BROOM-MOISTENER.

52,632.

Specification for Design.

Patented Nov. 12, 1918.

Application filed October 25, 1916. Serial No. 127,718. Term of patent 7 years.

To all whom it may concern:

Be it known that I, EVA MAY BROWN, a citizen of the United States, residing at Gardiner, in the county of Kennebec and State of Maine, have invented a new, original, and ornamental Design for Broom-Moisteners, of which the following is a specification, reference being had to the accompanying drawing, forming a part thereof.

Figure 1 is a perspective view; and

Fig. 2 is a bottom plan view of a broom moistener, showing my new design.

I claim:

The ornamental design for a broom moistener, as shown.

EVA MAY BROWN.

Witnesses:

GEORGE W. HESELTON,
HELEN FRANCES SHERMAN.
